US0D1055706S

(12) **United States Design Patent** (10) **Patent No.:** **US D1,055,706 S**
(45) **Date of Patent:** **** Dec. 31, 2024**

(54) **WATCH**

(71) Applicant: **META PLATFORMS TECHNOLOGIES, LLC**, Menlo Park, CA (US)

(72) Inventors: **Chunli Chen**, Seattle, WA (US); **Peter Wesley Bristol**, Seattle, WA (US)

(73) Assignee: **META PLATFORMS TECHNOLOGIES, LLC**

(**) Term: **15 Years**

(21) Appl. No.: **29/815,142**

(22) Filed: **Nov. 11, 2021**

(51) LOC (14) Cl. **10-02**

(52) U.S. Cl.

USPC **D10/32**

(57) **CLAIM**

The ornamental design for a watch as shown and described.

DESCRIPTION

FIG. 1 is a front perspective view of a watch showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict portions of the watch that form no part of the claimed design.

1 Claim, 7 Drawing Sheets
